UNITED STATES PATENT OFFICE.

MARIUS GUYOT, OF CLEVELAND, OHIO, ASSIGNOR TO ALUMINUM COMPANY OF AMERICA, OF PITTSBURGH, PENNSYLVANIA, A CORPORATION OF PENNSYLVANIA.

MOLD AND CORE.

Application filed January 30, 1926, Serial No. 84,846. Renewed July 1, 1929.

This invention relates to multipart metal molds for casting high melting point metals. It also relates to metal molds for casting articles comprising spaced, telescoping walls joined together by an end wall and by lateral webs spaced apart from the end wall. It further relates to a permanent mold cast, aluminum alloy, cylinder head for an internal combustion engine of the sleeve valve 10 type.

Cylinder heads for sleeve valve engines have heretofore been constructed of cast iron, so far as I am aware, although metals such as aluminum alloys possessed properties desirable for such articles. Attempts to make such parts of aluminum alloys by casting in sand or semi-permanent molds have not been commercially successful due, among other causes, to porosity in the castings through which water used for cooling could enter the combustion chamber. By this invention, however, sound, non-porous, commercially satisfactory cylinder head castings can be made. Furthermore, this invention also makes possible the casting of hollow articles comprising telescoping spaced walls joined together by an end wall and by lateral webs spaced apart from the end wall.

In the drawings attached to and forming a part of this specification:

Fig. 1 is a top plan view of an assembled mold embodying my invention;

Fig. 2 is a longitudinal view, partly in elevation and partly in section, taken substantially on line 2—2 of Fig. 1;

Fig. 3 is a transverse sectional view taken on line 3—3 of Fig. 1;

Fig. 4 is a side elevation of a core embodying my invention and shown in Figs. 1 to 3;

Fig. 5 is a top plan view of the core with certain sections being removed; and

Figs. 6, 7 and 8 are horizontal sections taken on lines 6—6, 7—7 and 8—8 of Fig. 4, respectively.

In the drawings, 1 designates a mold base which has slidably mounted on the top surface thereof two similar mold halves 2 which are pivoted together by an upright pin 3 extending into a perforation in the base 1.

Two other similarly shaped mold halves 4

are superposed on the first pair of mold halves and also pivoted together by the pin. The inner or contacting surfaces of the mold halves 2 are suitably recessed to form gate, feeder and casting cavities 5, 6 and 7, respectively, therebetween, in which articles of the desired configuration may be cast. The mold halves 2 are positioned, with respect to the base, by a pilot 8 projecting above the top surface of the base and seating in corresponding recesses 8^a in the mold halves 2. This pilot may be integral with the base but, as shown, is formed separately so that the same may be replaced by other pilots whenever it is desired to employ the base for making different castings. The top surface of the pilot may conveniently serve as an end wall for the casting cavity, and may include the use of an insert 9 of special shape. The insert 9 shown consists of a member seated and securely held in the pilot and having a top surface 9^a shaped to form the end wall of the desired casting.

The mold, herein shown, is constructed to form an outstanding flange 10 on the endless side wall of the casting 11. The mold halves 2 are provided on their top surface with filler blocks 12 of substantially the thickness of the flange, which blocks are held securely attached to the mold halves. The upper or superposed mold halves 4, which seat on the lower mold halves and filler plates have surfaces formed to receive the filler plates 12. It will be understood that when the mold halves are moved into engagement with each other they may be secured together at their free ends, as by the clamping bar 13 and hook 14.

A multipart core is carried by the superposed mold halves and clamped together and held in position by the latter, when the clamping bar and hook are in assembled position. This core projects into the casting cavity and forms inner walls therefor against which the molten metal may be cast. The core shown herein consists of a central, cylindrical section 16 having a reduced extension 17 at its free end, which projects into a correspondingly shaped perforation in the member 9 carried by the pilot. Surrounding

the central cylindrical section 16 are disposed a plurality of outer sections engaging therewith and with each other and having free ends which extend into the casting cavity but 5 stop short of the member 9 and the pilot 8, and are spaced apart from the cylindrical section and from the mold halves. These outer core sections cooperate with each other to form an endless hollow tubular wall. It 10 will be understood that the central section need not necessarily be cylindrical nor extend into contact with the bottom wall of the casting cavity. It will also be understood that the outer core sections may be 15 shaped to provide walls which are not necessarily endless or circular and that they form tubular walls of various cross sectional configurations.

As illustrated, the casting 11 formed in 20 the mold herein shown consists of endless outer and inner side walls 18 and 19, respectively, and an end wall 20, laterally extending webs 21 joining the walls 18 and 19 but spaced apart from the end wall 20. The 25 outer core part, which forms the space between the outer and inner side walls, may be made up of several parts of various forms, but I prefer to employ five parts, these parts comprising two oppositely disposed pairs of 30 relatively narrow sections 22 and a relatively large section 23. The small sections 22 which are arranged in pairs are relatively narrow and have their meeting faces 22^a cut away to form the cross webs 21 on the casting. 35 Each section 22 has an outstanding flange 22^b on its outer end to support the section from the top of the mold halves. The large section 23 is tubular in form with an outstanding flange 23^a at its outer end to rest on the 40 mold halves. It is provided with grooves 23^b to receive the pairs of smaller sections 22, which grooves extend entirely through the section 23 near its lower end (see Fig. 6) thereby forming openings through which enlarged portions of sections 22 project to form 45 the outer wall for the part 18 of casting 11. The free ends of all the sections 22 and 23 are preferably aligned as shown when assembled with the mold.

50 For the purpose of rendering easy the removal of sections 22 from a casting, they are provided with "draft" so as to be separable from each other in the casting. Although the amount of inclination of the substantially parallel outer and inner surfaces 55 necessary for such draft may be small, it has been indicated as large in Fig. 6 for the sake of clearness. That figure shows the sections 22 each having convergently inclined outer and inner surfaces 22^c and 22^d, respectively, below the web recess 22^e.

Additional similar core parts 24 are disposed on opposite sides of the main core to form certain walls of the cavity in which the 60 flange 10 is cast. Each part 24 seats in a

suitably shaped recess in the mold halves 4 and is provided at its outer end with a supporting flange 24^a and a handle 24^b. Each part 24 partly supports the flanges 22^b of a pair of sections 22.

70 A core constructed as above described, may be easily removed from its casting by first loosening the clamp 13 on the mold halves and then removing the central section 16. Then the larger outer section 23 can be removed by lifting it vertically out of the casting, after which the pairs of narrow sections 22 may be removed by pivoting each section about its inner corner 22^e as is permitted by the "draft" at the surfaces 22^c and 22^d and at the same time sliding the sections around the casting between the parallel walls until the sections clear the web 21, after which the sections are lifted vertically out of the casting. Such movements free the sections 22 85 from the cross webs 21 and the end wall of the casting, and permit their unobstructed removal from the casting. Then core parts 24 may be removed and the mold halves moved apart to free the casting.

90 It will be understood by those skilled in the art, that the various parts shown and described in detail hereinabove, have been given for the purpose of enabling others to practice my invention and not for the purpose of limiting the invention thereto. Various changes, not amounting to invention, may accordingly be made in the foregoing details without departing from the spirit of my invention. The scope of my invention is 100 defined in what is claimed.

What is claimed is:

1. A mold for casting a metal article which comprises a mold base, mold halves 105 slidably carried thereon and having their adjacent inner faces suitably recessed to form gate, riser and casting cavities for the said article, and a sectional metal core supported by the mold halves to project into and form inner walls of the casting cavity, the said core including a plurality of sections to form the space between the said inner and outer walls of the casting, one of the said sections being circular and cut away to receive pairs of sections, and other sections being arranged in pairs and disposed in the said circular section, each pair of sections being recessed to form therebetween lateral webs connecting the inner and outer walls and spaced apart from the end wall. 110

115 2. A mold for casting metals which comprises a mold base, mold halves slidably carried thereon and having their adjacent inner faces suitably recessed to form gate, riser and casting cavities for the article to be cast, and a sectional metal core supported by the mold halves to project into and form inner walls of the casting cavity, the said core including a plurality of cooperating sections forming an endless wall spaced 120

125 130

- apart from the side and bottom walls of the casting cavity, the said sections consisting of a section having wide, circumferentially extended, oppositely disposed free end portions, and narrow sections arranged in pairs engaging the side edges of the said portions, each pair of sections being provided with a recess therethrough at the parting line and remote from the free end thereof.
- 10 3. A mold for casting metals which comprises a mold base, mold halves slidably carried thereon and having their adjacent inner faces suitably recessed to form gate, riser and casting cavities for the article to be cast, and a sectional metal core supported by the mold halves to project into and form inner walls of the casting cavity, the said core including a plurality of cooperating sections forming an endless wall spaced apart from the side and bottom walls of the casting cavity, the said sections consisting of a section having wide, circumferentially extended, oppositely disposed free end portions, and narrow sections arranged in pairs engaging the side edges of the said portions, each pair of sections being provided with a recess therethrough at the parting line and remote from the free end thereof, and a central section within the endless wall forming sections and spaced apart from the free ends thereof.
- 15 4. A mold for casting a metal article which comprises a mold base, mold halves slidably carried thereon and having their adjacent inner faces suitably recessed to form gate, riser and casting cavities for the said article, and a sectional metal core supported by the mold halves to project into and form inner walls of the casting cavity, the said core including a plurality of sections to form the space between the said inner and outer walls of the casting, one of the said sections being circular and cut away to receive pairs of sections, and other sections being arranged in pairs and disposed in the said circular section, each pair of sections being recessed to form therebetween lateral webs connecting the inner and outer walls and spaced apart from the end wall, each pair of sections having inner and outer casting engaging side surfaces inclined convergingly toward their meeting edges.
- 20 5. A mold for casting metals which comprises outer mold sections, a series of core sections in contact with and supported by said mold sections, and an inner core encompassed and supported by said series of sections.
- 25 6. A mold for casting metals which comprises outer mold sections, a series of core sections in contact with said core sections throughout part of their outer surface and spaced therefrom for the remainder thereof to form part of a mold cavity, and an inner

core encompassed by said series of sections and spaced therefrom throughout part of its outer surface to form another part of the mold cavity.

In testimony whereof I hereunto affix my ⁷⁰ signature this 23rd day of January, 1926.

MARIUS GUYOT.
